UNITED STATES PATENT OFFICE.

IRWIN M. HERZIG, OF NEW YORK, N. Y., ASSIGNOR TO ELECTRIC SEALING MACHINE CORPORATION, OF NEW YORK, N. Y., A CORPORATION OF NEW YORK.

SEALING DEVICE.

Application filed December 20, 1921. Serial No. 523,658.

To all whom it may concern:

Be it known that I, IRWIN M. HERZIG, a citizen of the United States, and a resident of the city and State of New York, have invented certain new and useful Improvements in Sealing Devices, of which the following is a specification.

My invention relates to improvements in sealing devices such as are used for imprinting a die or stamp of sealing wax or a similar substance, upon envelopes, packages and the like, the said device being placed upon the sealing wax or similar substance while the same is still in a plastic 15 or viscous state.

In using such an impression seal of the ordinary construction, as heretofore employed, in rapid succession, it has been found that the die or stamping element 20 rapidly becomes heated by contact with the sealing wax which is in a hot condition, and because of this fact that the sealing wax adheres to the die or sealing medium and frequently clogs or fills up the depressions forming the design or inscription. It 25 is for the avoidance of this adhesion to which my device relates.

In the accompanying drawings Fig. 1 illustrates a bottom view of my device; 30 Fig. 2 illustrates a vertical cross-section on line 2—2 of Fig. 1.

Having reference to these figures the numeral 4 represents a metallic cup or bowl-shaped receptacle adapted to contain ice, 35 water or any other desired cooling medium, said cup having a central upper opening 5, preferably round as shown, which may be threaded as shown at 6 for the reception of the threaded lower end of handle 7.

40 A washer 7^a is seated at the opening be-

tween the lower portion of the handle and the upper surface of the cup, to make a water tight closure between the handle and the cup when the parts are in operative position.

The die or seal-carrying portion 8 forms the lower-most or bottom part of the receptacle, on the outer side of which part the desired design or inscription is engraved or stamped. This die-carrying portion consists preferably of a flat circular surface which may be integrally formed with the body of the cup or which, as shown may be in the form of a metal plate secured in an opening 9 at the lower part of the cup 55 by soldering the same thereto or by any other desired means such as screwing the same therein.

In manipulating my construction, the handle 7 is unscrewed and the cup is filled 60 with water or ice or any desired cooling medium whereupon the handle 7 and the washer 7^a are re-engaged with the cup, thus tightly closing the opening of the receptacle.

While I have shown my invention in one particular form of its application it will be understood that the same may be embodied in a variety of forms and in conjunction with any desired mechanism for 70 actuating the receptacle containing a cooling medium and a die, without departing from the spirit of my invention.

What I claim and desire to secure by Letters Patent is:

A sealing device comprising a receptacle adapted to contain a cooling medium, a die carried by said receptacle and means for depressing said receptacle and die.

IRWIN M. HERZIG.
